UNITED STATES PATENT OFFICE.

REGINALD A. FESSENDEN, OF BRANT ROCK, MASSACHUSETTS, ASSIGNEE, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

ELECTROMAGNETIC INDICATOR.

1,172,018.

Specification of Letters Patent. Patented Feb. 15, 1916.

Application filed March 14, 1908. Serial No. 421,220.

To all whom it may concern:

Be it known that I, REGINALD A. FESSENDEN, a citizen of the United States, residing at Brant Rock, in the State of Massachusetts, have invented a certain new and useful Electromagnetic Indicator, of which the following is a specification.

My invention relates to electric indicating instruments, or means for detecting the character and changes in currents, something after the fashion of galvanometers, and especially adapted for use with alternating currents though of course it is equally suitable for continuous currents and other electric manifestations by which a field of force is altered. Its primary objects are to provide a more sensitive and reliable indicating instrument, to increase the power of the controlling field and avoid the ill effects of heat in the conductors, and otherwise improve such mechanisms, as well as provide superior means for observing or recording the changes of current, etc. These objects and other advantages to hereinafter appear are attained by means such as illustrated in two forms in the accompanying drawing, wherein—

Figure 1 is a central vertical section of one form of indicator; Fig. 2 is a side elevation of the indicating part of a modified form of instrument, and Figs. 3 and 4 are sections on the line (3, 4) of Fig. 2, showing two positions of the indicating wires.

One of the chief difficulties in obtaining a sensitive indicating instrument of this general type, is that the magnetic field employed is limited because the exciting current is limited owing to the wires becoming heated when they carry heavy currents. I not only obviate this, but also obtain great magnetic concentration and otherwise improve the sensitiveness of such instruments by keeping the field conductors cool, which may be done in various ways as by placing the entire apparatus in a chamber cooled as by liquid air or other refrigerant, or else by making the field conductors hollow and cooling them by contained refrigerating fluid. Also I make the readings more delicate by utilizing the double effect of two or more moving elements which approach and recede from one another on the passage of currents to be indicated. Thus, in Fig. 1 I provide a loop of a hollow conductor 6, through which is circulated liquid air or other refrigerant, which has the double effect of lowering the resistance to current and also carrying away the heat, whereby very heavy currents may be employed, as for instance, several hundred amperes. A part or all of this field conductor loop 6 is preferably inclosed in vessel 7 which is preferably vacuous and thus removes opposition to motion of the moving parts, as well as preventing the disturbances of air currents. Also within this chamber 7, and in the field of the conductor loop 6, I provide a fine wire loop 11, 12, which may be conveniently kept under regulable tension and is provided with thickened portions 13 in order to increase the visibility or the width of the shadow of the wires seen through the window 8, and to make them vibrate more definitely. The wire loop may be balanced and stretched by a pulley 14 attached to a spring 15 and to an armature 16 which is drawn down against the effort of spring 15 by the core 17 of a coil 18, whose strength is regulated by the battery 19 and adjustable resistance 20. Of course any other means for regulating the tension on the wires may be employed and this tension will adjust the natural period of vibration of the indicating wires 11 and 12. It will be evident that the relative positions or motions of the wires 11, 12 when under the influence of current in conductor 6 and the coöperating current to be indicated which flows through by the terminals 9, 10, will indicate the voltage of the current or the period of alternating currents, etc., and that by reason of the field being particularly strong and the indicating wires particularly free to move, the instrument is very sensitive and easily read. Of course any desired means may be used for recording the motions of the indicating wires.

In the modification shown in Figs. 2, 3, 4, the apparatus is adapted to be placed in a chamber cooled by liquid air or other refrigerant in any convenient way; or it may be used bodily in place of the wires 11 and 12 in the apparatus of Fig. 1, replacing the wires 13 therein. It comprises essentially a field of force such as produced by the magnetizing coil 21, and a series of wires or a coil of the wire 22 stretched in the field so as to lie in two parallel planes, as indicated in

Figs. 3 and 4. It is preferable to so mount them on bars 24 that normally the series of wires 23 alternate in position with the series 23^a, so that light coming in the direction of 5 the arrow in Fig. 3 is shut off by the wires. When a current passes through the wires 23 however, the coöperation with the magnetic field will cause them to shift position so that 10 they will stand in register and permit light to pass through as indicated in Fig. 4. This effect can be observed directly by the eye or telescope, or obviously recording means could be employed such as a traveling photo sensitiv- 15 esurface 26 on rolls 27 exposed to a portion of the light let through a perforated screen 28. Obviously a tension adjusting means, such as illustrated in Fig. 1 could also be applied to the wires in Fig. 2 or they may be adjusted by screws 25 so as to regulate 20 their natural period of vibration. In this device again, the indication is produced by the cumulative effect of the motion of the indicating wires, which makes the instrument very sensitive in addition to the ad- 25 vantage of using very strong currents for the magnetic field.

Having thus described my invention and illustrated its use, what I claim as new and desire to secure by Letters Patent, is the fol- 30 lowing:

1. An electromagnetic indicator comprising a loop of indicating wire whose members are adapted to be relatively laterally moved by changes in a field of force, and a loop of 35 hollow cooled conducting wire arranged to form a field of force, substantially as described.

2. A galvanometer comprising a conductor adapted to produce a field of force, two 40 parallel sets of stretched wires suspended in said field, and means for observing their movements relative to each other.

3. A galvanometer comprising a conduc-

tor adapted to produce a field of force, two parallel sets of stretched wires suspended in 45 said field, and means for observing and recording their movements relative to each other.

4. A galvanometer comprising a conductor having parallel portions adapted to produce a field of force, and plurality of wires stretched in said field of force and adapted to give an exaggerated indication by motions in opposite directions, substantially as 50 described.

5. A galvanometer for high frequency currents comprising a loop of hollow water cooled conductor adapted to produce a field of force, and a plurality of oppositely movable wires suspended in said field of force 60 and adapted to be altered in their spacing apart by variations in said field, substantially as described.

6. In a galvanometer comprising a device adapted to produce a field of force, an indicator including two sets of parallel wires suspended in said field and arranged to move laterally in opposite directions, and means to observe variations in the amount of light admitted through the wires when they vi- 70 brate.

7. A galvanometer comprising a field producer formed of a hollow conductor cooled by liquid therein, and an indicator having several sets of parallel closely spaced wires 75 mounted in said field, and means for observing the motions of said wires relative to each other, substantially as described.

In testimony whereof I have hereunto signed my name in the presence of the two 80 subscribed witnesses.

REGINALD A. FESSENDEN.
